UNITED STATES PATENT OFFICE.

ALFRED CARR, OF DAYTON, OHIO.

EMBROIDERING AND DARNING ATTACHMENT FOR SEWING-MACHINES.

1,169,236.

Specification of Letters Patent. Patented Jan. 25, 1916.

Application filed April 29, 1915. Serial No. 24,724.

To all whom it may concern:

Be it known that I, ALFRED CARR, a citizen of the United States, residing at Dayton, in the county of Montgomery and State 5 of Ohio, have invented certain new and useful Improvements in Embroidering and Darning Attachments for Sewing-Machines; and I do declare the following to be a full, clear, and exact description of the 10 invention, such as will enable others skilled in the art to which it appertains to make and use the same.

This invention relates to improvements in sewing machines and more particularly to 15 embroidery and like attachments therefor.

The object of the invention is to provide an attachment of this character so constructed as to adapt it to be easily attached to and detached from the presser bar of a 20 sewing machine and to be raised by the action of the needle carrier from the pressure on the material as the needle is withdrawn from the latter, so as to permit the movement of the cloth or material in various 25 directions and to any desired distance, as the varying nature of the work being performed may require.

Another object is to provide an attachment of this character which is automatic 30 in its adjustment to heavy and light fabrics.

Another object is to provide a device of this character so constructed as to prevent springing of the needle during the feeding back and forth of the material, while at the 35 same time permitting a clear vision of the material being operated upon.

With these and other objects in view the invention consists of certain novel features of construction, and the combination and 40 arrangement of parts hereinafter described and claimed.

In the accompanying drawings:—Figure 1 represents a side elevation of a portion of the head of a sewing machine with this improved attachment applied, showing the needle bar in lowered position; Fig. 2 is a similar view with the needle bar shown in raised position, whereby the attachment is also raised; Fig. 3 is a detail perspective 50 view of the attachment detached; Fig. 4 is a horizontal section taken on the line 4—4 of Fig. 1.

In the embodiment illustrated, 1 denotes the head of a sewing machine of ordinary 55 construction having the usual vertically reciprocating needle bar 2 and presser foot

bar 3, said needle bar being shown provided with the usual clamping screw 4 for controlling the needle clamp, said screw extending laterally from said bar 2. 60

This invention comprises an attachment for connection with the presser bar 3 from which the ordinary presser foot has been removed as unnecessary for the class of work to be performed by this attachment, and to 65 provide for the substitution of said attachment. This attachment comprises a shank 5 having a laterally extending bifurcated arm 6 projecting from its upper end and which is designed to be engaged with the 70 presser bar 3, the furcations of said arm being slipped into slides carried by the presser bar. This standard 5 has a laterally extending foot 7 at its lower end projecting in a direction opposite to that of the arm 6 and 75 which is here shown substantially annular in form, with a lip 8 projecting from the front portion thereof and provided with an aperture 9 for the passage therethrough of the needle when the device is applied, said 80 aperture being designed to form a guide for the needle and to prevent breakage thereof caused by springing, which is incident to the pulling of the material in darning. It is to be understood that the thread goes 85 down through this aperture 9 and a side pull will be exerted on the foot and not on the needle, thereby preventing all possibility of the needle being sprung and broken. A large opening at the rear of the needle 90 guiding opening 9 enables the operator to inspect the work being accomplished at all times, especially to observe the needle when it enters the material.

An L-shaped member 10 extends laterally 95 from one side edge of the shank 5, the long arm of said member being attached to the shank and preferably made integral therewith, while the short arm projects forwardly and has attached thereto an upstanding 100 member 11, the stem 12 of which is of a length suitable to position the hook 13 at the free end thereof ready for engagement by the laterally projecting screw 4 carried by the needle bar 2, when said needle bar is 105 raised sufficiently to cause the needle carried thereby to pass out of the material being sewed, said hook carrying member 11 being designed to form a stop extending into the path of the clamping screw of the needle bar, and thereby being raised with said 110 screw on the raising of the needle bar so

that the attachment of which said member forms a part, is lifted sufficiently to permit the material lying thereunder to be moved in any direction desired.

5 From the above description it will be obvious that by constructing and attaching this device as set forth, the attachment will automatically adapt itself to material of varying thicknesses, and it will be automatically lifted on the raising of the needle bar and lowered on the lowering thereof, thus avoiding all necessity of the operator being compelled in any way to manipulate the attachment during the operation in 10 which it is employed.

15 It is of course understood that in darning, etching, embroidering, and similar work, the operator does not use the feed movement of the sewing machine but it is essential, in order to perform good work, that pressure be applied to the material being sewed while the shuttle is passing through the loop of thread formed under the bed plate of the sewing machine. Otherwise, the machine 20 will skip stitches and the work will be unsatisfactory. It will also be observed that this attachment is preferably constructed, as shown, in a single piece which may be stamped out of sheet metal and thus render 25 the construction thereof very economical. It will also be obvious from the above description that no stop will be necessary during the operation of this attachment for the

purpose of raising or lowering the attachment, as it will automatically perform this 35 operation without any skipping of stitches.

I claim as my invention:—

An attachment for sewing machines comprising a shank having a laterally extending bifurcated arm projecting from its upper 40 end for attachment to the presser foot thereof, a laterally extending foot at the other end projecting in the direction opposite to that of said arm, said foot being substantially annular in form and having a lip projecting from the front portion thereof, said lip being provided with an aperture for guiding the needle to prevent breakage of the latter, an arm extending from one side edge of said shank and integral therewith, 45 an additional arm projecting forwardly from the first named arm, a stem projecting upwardly from said additional arm, the free end of said stem being integrally connected with a forwardly extending hook disposed 50 in the path of the clamping screw of the needle bar, whereby the attachment is automatically raised by the latter.

55 In testimony whereof I have hereunto set my hand in presence of two subscribing witnesses.

ALFRED CARR.
